UNITED STATES PATENT OFFICE.

ROBERT S. HENDERSON, OF ALMA CENTER, WISCONSIN.

CALCULATING MACHINE.

Application filed April 27, 1921. Serial No. 464,794.

To all whom it may concern:

Be it known that I, ROBERT S. HENDERSON, a citizen of the United States, residing at Alma Center, in the county of Jackson and State of Wisconsin, have invented new and useful Improvements in Calculating Machines, of which the following is a full, clear, concise, and exact description, reference being had to the accompanying drawings, forming a part of this specification.

My invention relates to a calculating machine and it has special reference to such devices as may be employed for the rapid and accurate ascertainment of interest on any probable amounts for various periods of time. Moreover, my invention relates to devices of the aforementioned character wherein the locating of decimal points in the various ascertained amounts is correctly effected through the agency of a mechanical contrivance forming a part of my present invention.

One object of my invention is to provide a device of the character indicated above which is compact and capable of being expeditiously operated by unskilled persons and, at the same time, is accurate although it possesses an exceptionally large operating range.

Another object of my invention is to provide a device which may be employed for mechanically ascertaining the number of days intervening between two known dates or which may serve to determine a certain future calendar date when given a definite calendar date and the intervening period of time in days at the termination of which the said future calendar date will arrive.

The device of my present invention, which I designate as an interest calculating machine, is of great convenience in the rapid calculation of interest on interest bearing principals at any of the common interest rates for any of the usual interest periods of time. For this purpose, it is well adapted for use in banks where it is desired to determine interest amounts for any of the usual rates of interest. Again, my device comprises a very few number of parts none of which is delicate or intricate and is capable of being operated by unskilled persons who do not require any special training to use it expeditiously. My device, moreover, is simple and economical to construct and by reason of its simplicity may be marketed for a very reasonable sum.

For a better understanding of my invention reference may be had to the accompanying drawings; in which,

Fig. 1 is an elevational side view of a device embodying my invention; 60

Fig. 2 is an end elevational view of the device illustrated in Fig. 1; 65

Fig. 3 is an elevational sectional view taken on the line 3—3 of Fig. 2; 70

Figs. 4, 5 and 6 are fragmentary, elevational and sectional views illustrating various details embodied in my invention; and

Fig. 7 is an enlarged side elevational view of a device embodying a form of my invention, the same being enlarged to such an extent that it is possible to illustrate therewith the manner in which a problem may be solved thereupon. 75

Referring now more particularly to the drawings, my device comprises a frame member having a base 10 from which rise legs 11, cross pieces 12 and side pieces 13 being mounted on said legs whereby a cradle is formed. Suspended within the aforesaid cradle is a shaft 14 upon which are mounted spiders 15—15, 16 and 17. Sheets of any desired material are wrapped around these spiders to form cylindrical surfaces 18, 19, and 20 thereabout, respectively. In this connection it will be noted that the cylinders 19 and 20 are so mounted on an enlarged collar portion of the left hand spider 15 and are so locked against longitudinal movement therealong by a collar 21 that said cylinders 19 and 20 may be rotated independently of the cylinder 18. Again, as will be noted from a consideration of Figs. 5 and 6 in connection with Fig. 3, the outer ring portion of the spider 16 is provided with a plurality of circumferentially extending sockets or pits 22 while the outer ring portion of the spider 17 has mounted thereupon a spring member 23, having associated therewith a detent 24 which is adapted to be biased normally into the sockets 22 to hold the cylinders 19 and 20 together unless sufficient force is exerted whereby one may be moved in relation to the other, the detent 24 then slipping over the sockets 22 by reason of the flexibility of the spring 23. The purpose of this construction will be hereinafter more fully set forth. 80

A knob or handle 25 is provided at each end of the shaft 14 whereby the cylinder 18 may be rotated when desired. 85

A knob or handle 25 is provided at each end of the shaft 14 whereby the cylinder 18 may be rotated when desired. 90

Extending transversely of the cylinders heretofore described, is what I hereinafter will call a registry bar 26, having a slot 27 extending parallel with its longer dimension. 5 This bar is secured to one of the side frames 13 in such manner that it fits quite closely to the surface of the cylinder 18, as shown most clearly in Fig. 4.

A movable bar 28 provided with a plurality of indicating points 29 is provided at its lower left hand edge with ratchet teeth 30. This bar is adapted to be moved longitudinally along the registry bar 26 by reason of its disposition in a longitudinally extending 10 pocket as best shown in Fig. 4, this pocket being formed by the angle bar 31 being disposed on top of the bar 26.

Likewise mounted on the lower edge of the bar 26 and at the left side of the device is a 20 half circular dial member 32 over which moves an indicating pointer 33, the latter being fastened to a gear 34, the teeth of which are adapted to engage the ratchet portion 30 of the bar 29 whereby, upon the movement 25 of the pointer 33 to various positions around the dial 32, the bar 28 is moved laterally to position the indicating points 29 at various precalculated positions with respect to the indicia (which will hereinafter be described) 30 observable through the slot 27. It will be noted that at the right hand end of the bar 26 a slot 35 is engaged by an upstruck finger 36 on the angle bar 31, thus limiting the 35 lateral movement of the bar 28 within certain predetermined limits and, moreover, serving to support this bar in said movement.

Referring now to the calculating function of my device it will be understood that on that portion of the cylinder 18 designated as 40 37 the number of days is indicated as shown, the position of these numbers of days being predetermined by calculation and being placed on the cylinder in predetermined co-ordination with the rows of figures appearing 45 in the columns on the right hand portion 38 of the cylinder, it being noted that these columns are numbered from 10 to 90 and that there are eight places in each row of figures. Of course, I may have any number 50 of places in each row, depending upon the range of operation I desire.

The portion of the registry bar 26 which is co-extensive with the "number of days" portion on the cylinder 18 has indicated thereupon a plurality of amounts designated as 55 "Per cent—%—rate of interest". The indicating points 29 on the bar 28 are numbered from 10 to 90, these numbers corresponding to those appearing at the heads of the columns on the portion 38 of the cylinder. Further, the dial 32 is divided into equi-spaced circumferential portions which are 60 designated from .10 to 1,000,000, and it is noted that the pointer 33 can be moved to any desired designation and there frictionally se-

cured through the use of a spring biased button 39.

As I have above intimated the amounts appearing in the columns designated "10 * * * 90" have been arrived at by 70 precalculation and are placed on the cylinder in co-ordinate relation with the number of days. At the same time the interest rates appearing on the registry bar have likewise 75 been so co-ordinated that when the cylinder 18 is moved relatively to the stationary registry bar, an observer may be able to read a desired result directly from the figures in 80 said columns "10 * * * 90", which are observable through the slot 27. In this connection it should be noted that the slot 27 extends all the way across the bar and that the 85 number of days are observable therethrough as shown in Fig. 7.

In addition to the numbers of days which are indicated on the space 37 of the cylinder 18, a calendar is located at the extreme left hand edge of said cylinder and, as shown in Fig. 7, the days of the months under each 90 particular month are arranged consecutively in much the same fashion as if any ordinary calendar were placed in a column and each succeeding day placed under the preceding day. The cylinder 19 has arranged thereupon, as shown, consecutive numbers from 1 to 365, it being understood that these numbers parallel the days on the edge of the cylinder 18 and that the name of a month appears on the cylinder 18 at a corresponding 95 space on the cylinder 19. 100

Finally, the independently rotatable cylinder 20 has the calendar by months and days mounted therearound in exactly the same fashion and in parallel co-ordination to those displayed on the left hand edge of 105 the cylinder 18.

Having now described the physical construction of my device I will illustrate the principle of its operation by stating a problem as shown in Fig. 7 and point out the manner in which the same may be solved in a simple and expeditious manner with my device. 110

It is required to find the interest on \$1,347.90 for the number of days which 115 intervene between June 6 and July 3, at a rate of five percent per annum.

The first operation involved is that required to determine the number of days for 120 which interest must be paid on the sum designated. The cylinder 18 is first turned relative to the bar 26 until the earlier date, June 6th, is observable, as shown through the slot 27 near the extreme left end thereof. The cylinder 19 is next turned until a stop 39, which is positioned on said cylinder 125 opposite the figure zero thereupon, engages a projection 40 on the side frame 13 just opposite the slot 27. It should be understood also that there are 365 of the sockets 130

22, each of said sockets corresponding to one of the numbers appearing on the cylinder 19. The next operation is the turning of the cylinder 20 to the right until "June 6" is observable through the slot 27. This is possible because such cylinder 20 can be turned to overcome the engagement between the button 24 and the socket 22, inasmuch as the cylinder 19 is held stationary against clockwise movement by the stop 39 abutting against the shoulder 40. The designation of the three cylinders is therefore "June 6 * * * 0 * * * June 6." If now, the cylinder 20 be turned in an anti-clockwise direction until the designation "July 3" is observable through the slot 27 and remembering that the spring member 23 locks the cylinders 19 and 20 together, it will be seen that when said designation "July 3" is observable, there will also appear through the slot 27 that number of days on the cylinder 19 which intervenes between June 6th and July 3rd, since zero was initially set opposite June 6th and since the cylinders have been moved backward together.

In the problem stated we find that 27 is the number observable through the slot 27 and therefore this is the number of days during which interest must be paid. Having determined the number of days we next revolve the cylinder 18 until we find the figure "27 days" observable through the slot 27 and under the interest rate at which we are calculating, in this particular instance 5. When the cylinder 18 has been rotated into this position we are now ready to read off the interest amount for the various sums making up the principal amount.

It will be observed that the columns on the portion 38 on the cylinder are numbers 10, 20, etc., up to 90, inasmuch as the principal amount upon which we are calculating, has as its first significant figure 1 and, inasmuch as this figure 1 stands in the fourth position to the left of the decimal point we read in column 10 the amount of interest which is due for twenty seven days on \$1,000.00. In order to determine the position of the decimal point in the interest amount just found, by looking at the row of figures in column 10 observable through the slot 27, we turn the indicator 33 to the designation 1000 on the dial 32. This causes a movement of the bar 28 to bring one of the pointers 29 designated as 1 between two of the figures in the row of figures in column 10 which we are observing. The decimal point must therefore be placed as determined by the designating point 29 and it will be seen that the sum which is read from column 10 is \$3.75.

We next proceed to find the interest on \$300.00. Proceeding in the same manner we read under column 30 since 3 is the first significant figure in \$300.00 and at the same

time we move the indicator 33 to the "100" position whereby the decimal point is indicated as shown by the designating point 29 marked 2 on the bar 28.

In like manner we proceed to find the interest for \$40.00, then for \$7.00 and finally for \$.90 and after setting these sums down as shown at the right of Fig. 7, we add the amount together and thereby determine the correct interest amount for the principal 75 amount designated.

From the foregoing description it will be obvious to those skilled in the art that I have provided a device wherein all of the necessary calculations for finding the interest on a designated principal are made with a minimum expenditure of time since only one adjustment is needed after the number of days for which interest must be paid is calculated, with the exception that 85 it is necessary to determine the correct position of the decimal point in the interest amount read.

Further I believe that the manner in which I determine the number of days between any certain dates is entirely novel and it will be observed that this particular calculation is so combined with the interest calculating function of my machine that an extremely simple and compact device 90 ensues.

I have provided a "linolite" 41 positioned just above the slot 27 and have shaded this light by a transversely extending hood 42 whereby the figures which are observed 100 through the slot 27 may be read with a minimum of effort.

While I have described but one embodiment of my invention it is obvious that many modifications therein may occur to those skilled in the art and I desire, therefore, that my invention be considered in its broadest aspects and be limited only by the showing of the prior art and by the scope of the appended claims.

Having thus described my invention what I now claim as new and desire to secure by Letters Patent is:

1. An interest calculating device comprising a rotatable cylinder having groups of figures arranged thereupon in columns and rows, the groups of figures in each of said columns representing interest sums for principals possessing the same significant figure and at different interest rates for different interest periods and the groups of figures in each of said rows representing interest sums for principals of all amounts and for designated significant figures, a register bar whereby selected rows comprising said groups of figures may be exhibited, a decimal indicator adjacent to said register, a dial having arranged thereon figures representing multiples of principal amounts, and a pointer playing over said dial and adapted 130

to move said decimal indicator in accord with the interest bearing principal in order to automatically position the decimal point on the interest amount corresponding to the interest bearing principal.

2. An interest calculating device comprising a rotatable cylinder on the surface of which interest periods measured in time are arranged in alignment with interest on amounts in the form of principals for various interest bearing principals, a transverse bar upon which interest rates are arranged, means for moving said cylinder with said transverse bar relatively to each other in order to move predetermined interest periods in alignment with the desired rates of interest whereby the interest amounts for the desired principal may be determined, a register where said interest amount may be exhibited, an indicator upon which figures are arranged in alignment with the columns of figures representing interest amounts, pointers severally affixed to said figures on said indicator for locating the decimal point in the interest amount exhibited at said register, a dial having arranged thereon figures representing multiples of principal amounts, and a pointer playing over said dial and adapted to move said indicator in accord with the value of the interest bearing principal.

3. An interest calculating device comprising a rotatable cylinder on the surface of which interest periods are grouped in columns representing various rates of interest and in alignment with said interest periods are grouped interest amounts arranged in columns that represent interest bearing principals of the nine possible significant numbers, a register bar where interest amounts may be exhibited by rotating said cylinder relative thereto, an indicator adjacent to said register bar for indicating the decimal point in said interest amount, and means for locating said indicator in accord with the interest bearing principal upon which the interest value for the proper interest period is desired.

4. In a machine of the character described comprising a rotatable cylinder having circumferentially arranged thereupon divisions which are labeled with the days of a calendar year and separate figure columns adjacent thereto each for a designated interest rate, the figures representing interest periods, means adjacent to said divisions comprising a plurality of rotatable discs bearing respectively divisions representing the days of a year and divisions numbered from zero to 365 whereby the interest period between two dates may be indicated and the proper figure of said columns may be thereupon selected, said cylinder at the end opposite from said divisions also bearing separate columns of interest amounts each for a desig-

nated significant figure, the amounts being in horizontal alignment with their corresponding figures representing interest periods, and a horizontal fixed indicator bar extending over the width of said cylinder 70 and discs.

5. In a device for determining the interest amount on a given principal, a surface having a plurality of columns of figures thereupon representing interest amounts, a 75 registry bar extending transversely of said columns, said surface and said bar being relatively movable whereby said bar may be brought into registry with any row of figures in said columns, a decimal bar for 80 determining the position of the decimal point in said registered row of figures, a dial, and a cooperating pointer for moving said decimal bar in accordance with the position of the first integer of said principal 85 with respect to the decimal point.

6. In a device for determining the interest amount on a given principal, a surface having a plurality of columns of figures thereupon, a registry bar extending transversely of said columns, said surface and said bar being relatively movable whereby said bar may be brought into registry with any row of figures in said columns wherefrom the figures of said interest amount 90 may be read, and means adjustable in accordance with the position of the first integer in said principal with respect to the decimal point to indicate the position of the decimal point in said interest amount. 95

7. In a device for determining the interest on a given principal, a surface having a plurality of columns of figures thereupon, a registry bar extending transversely of said columns, said surface and said bar being relatively movable whereby said bar 100 may be brought into registry with any row of figures in said columns, indicating means to determine the position of the decimal point in said registered row of figures in accordance with the first significant figure of the principal bearing sum, and means comprising a rack portion on said indicating 105 means and a gear, the latter being movable to a plurality of positions corresponding to the position of the first figure of the principal with respect to the decimal point, for moving said indicating means to designate the position of the decimal point in the interest read from said registered row of 110 figures. 115

8. In a device for determining the interest on a given principal for a given interest period of time and at a given interest rate, a surface having a plurality of columns of 120 figures thereupon, a registry bar extending transversely of said columns, said surface and said bar being relatively movable whereby said bar may be brought into registry with any row of figures in said col- 130

umns wherefrom the figures of said interest amount may be read, means comprising an indicator movable to positions corresponding to each column for determining the position of the decimal points in the registered row of each column, the columns from which the interest amount is read on said rows being determined by the significant figure in said principal, a dial having arranged thereon figures representing multiples of principal amounts, and a pointer playing over said dial and adapted to move said indicators as a unit in accordance with the position of the significant figure of the principal with respect to the decimal point.

9. An interest calculating device comprising a rotatable cylinder on the surface of which figures representing interest periods are arranged in alinement with figures representing interest amounts that in turn are arranged in nine columns corresponding to the nine significant figures representing interest bearing principal amounts; a transverse bar upon which figures representing interest rates are arranged in coincidence with columns comprising the interest-period figures arranged on said cylinder; a register bar wherat said interest-amount figures may be exhibited; means for effecting rela-

tive movement between said cylinder and said register bar in order that predetermined interest-period figures may be alined with the desired interest-rate figures in order that the interest amount for the desired principal interest rate and interest period may be determined; a decimal indicator upon which figures representing the first significant figures of interest bearing principals are arranged to subtend the said columns of interest-amount figures on said cylinder, said decimal indicator figures representing the first significant figure of the interest bearing principals having severally affixed thereto indicators for locating the decimal points in the interest-amount figures exhibited at said register bar; a dial having arranged thereon figures representing multiples of said interest-bearing principal amounts; and a pointer playing over said dial and adapted to move said decimal indicator in accordance with the amount of the interest bearing principal.

In witness whereof, I have hereunto subscribed my name.

ROBERT S. HENDERSON.
